DESIGN FOR A TELEPHONE OPERATOR'S CHAIR

Wolfe W. Brown, Short Hills, N. J., assignor to Bell Telephone Laboratories, Incorporated,
New York, N. Y., a corporation of New York

Application February 3, 1943, Serial No. 109,414

Term of patent 14 years

To all whom it may concern:

Be it known that I, Wolfe W. Brown, a citizen of the United States, residing at Short Hills, in the county of Essex and State of New Jersey, have invented a new, original, and ornamental Design for a Telephone Operator's Chair, of which the following is a specification, reference being had to the accompanying drawing, forming a part thereof.

The figure is a view, in perspective, of a telephone operator's chair, showing my new design.

I claim:

The ornamental design for a telephone operator's chair, as shown.

WOLFE W. BROWN.
